UNITED STATES PATENT OFFICE.

JAMES W. DUNDAS, OF DETROIT, MICHIGAN.

AUXILIARY LIFTING ARRANGEMENT FOR AEROPLANES.

Application filed November 29, 1926. Serial No. 151,319.

This invention relates to improvements in auxiliary lifting arrangements for aeroplanes, and consists essentially of shells or casings adapted to be secured to the upper wings and the top of the fuselage of aeroplanes, said casings having an arrangement of gas bags in them to increase the lifting capacity and buoyancy of the machines on which they are mounted.

Another object of the invention is to provide an auxiliary lifting arrangement for aeroplanes which may be applied to any type of aeroplane, and in which the casings and gas bags are so positioned as to materially increase the stability of the machines to which they are secured.

A further object of the invention is to provide one common gas line from which all the gas bags both on the wings and over the fuselage may be filled; and to so construct the gas bags that additional ones may also be inserted and inflated in any portions of the fuselage not otherwise utilized so as to further add to the lifting ability of the machine.

Yet another object of the invention is to so mount the casings on the wings that both the casings and the wings may be turned to a limited extent about a horizontal axis so as to facilitate the handling of the aeroplane particularly when ascending or descending.

With these and other objects in view which will become apparent as the specification proceeds, an embodiment of the invention is hereinafter more fully described with the aid of the accompanying drawings, in which:

Figure 1 illustrates a side view of an aeroplane provided with my auxiliary lifting device.

Figures 2 and 3 are sections on the lines II—II and III—III of Figure 1.

Figure 4 is a detail showing the tilting mechanism for the wings and the wing casings and gas bags.

Figure 5 is a section on the line V—V of Figure 4.

Figure 6 is a fragmentary view showing part of the gas line and valves controlling the filling of the bags.

Figure 7 shows a section through one of the wing gas bags.

Referring to the drawings, 1 designates an aeroplane having a fuselage 2 and wings 3. To the upper portion of the fuse-

lage the lower margins 4 of a shell or casing 5 are secured. This casing consists of substantially rigid material and is frequently made of aluminum. Moreover while a solid 60 casing is shown in the drawings it may be made in any desired manner so long as it effectively supports the sides of the gas bags 6 contained therein, which latter are preferably arranged one behind the other. 65 The outer sides of these bags are supported by the inside of the casing 5 and the top of the fuselage, and the ends of the bags bear against fabric partitions 7 which are attached to cross members 8. A gas line 10 extends longitudinally under the shell and has a branch 11 connected to each gas bag 6. The branches are preferably each provided with a gas valve 12.

To the wings 3 wing casings 13, similar 75 in general construction to the casing 5, are secured. These wing casings are also filled with a series of bags 14 similarly separated by fabric partitions 15 supported on cross braces 16, the ends of which are fastened to 80 the wing casings. Lateral gas lines 17 extend from the gas line 10 to the wing bags 14.

In cases where a portion of the space 85 within the fuselage is not employed for other purposes that portion may be utilized for holding additional gas bags 19, which are filled from a pipe connection 20. Where these additional gas bags are provided it is preferable that they should be of such size 90 as to fill the space between two adjacent fuselage supports 21, and I prefer to attach a fabric partition between them as indicated at 22.

The wing casings may either be rigidly 95 secured to the main casing 5, or the former may be so mounted on the latter that the wing casings may turn to a limited extent about a horizontal axis together with the wings on which they rest. In the latter case 100 I prefer to provide outwardly projecting bolts 23 in the casing 5 and circumferentially slotted openings 24 in the inner ends of the wing casings. In that case the wings are usually pivotally mounted on the sides 105 of the fuselage as on a shaft 26 which preferably extends right across the fuselage. On this shaft 26 is a worm wheel 27 which meshes with a worm 28 on the spindle 31. The spindle is supported in suitable bearings 110 29 and terminates in a handwheel 30 located in such position as to be within easy reach

of the operator of the aeroplane. Again the wing arrangement just described may also be employed in connection with a dirigible lighter than air machine.

5 When my auxiliary lifting arrangement, is to be applied to an aeroplane already constructed I usually leave the wings, and also the wing casings, rigidly attached to the fuselage and to the main shell or casing respectively; but when constructing an aeroplane to which my attachment is to be applied it is found that the movable wing arrangement facilitates the handling of the machine. It will also be noted that the gas bags are so constructed that their lifting power alone is not sufficient to prevent a descent being made.

10 In order to provide gas bags having sufficient cubic capacity for my purpose it will be noted that immediately above the top of the fuselage the main shell 5 projects laterally outwards as indicated at 5^a, and again the undersides of the wing casings extend in front of the wings and the shells or casings 15 13^a are supported by forwardly projecting braces 32.

15 While in the foregoing a preferred construction of the invention is described, it is understood that alterations and modifications 30 may be made thereto provided the said alterations and modifications fall within the scope of the appended claims.

20 What I claim as my invention and desire to secure by Letters Patent is:

25 1. In an arrangement of the character described, the combination with an aeroplane having a fuselage and wings attached to said fuselage, of a main casing mounted on the upper side of said fuselage, wing casings

on said wings and secured to said main casing, a plurality of gas bags in each of said casings, and a gas line under said bags and connected to them.

2. In an arrangement of the character described, the combination with an aeroplane 45 having a fuselage and wings, of a main casing attached to the upper side of said fuselage, wing casings on said wings secured to said main casing, sets of laterally disposed braces in all of said casings, a gas bag between each adjacent pair of sets of braces, and means for filling said gas bags.

3. In an arrangement of the character described in claim 2, the combination wherein the wing casings are so mounted on the main 55 casing as to permit a limited rotary movement of the former about the latter.

4. In an arrangement of the character described the combination with an aeroplane having a fuselage and wings pivotally 60 mounted thereon, of a main casing mounted on said fuselage, wing casings mounted on said wings, said wing casing inner ends being so secured to said main casing as to be permitted a limited rotary movement 65 about the latter on a horizontal axis, a shaft extending across said fuselage, one of said wings secured to each end of said shaft, a worm wheel on said shaft, a spindle supported by said fuselage, a worm on said 70 spindle in engagement with said worm wheel, means for turning said spindle, a plurality of gas bags in each of said casings, sets of lateral braces in each of said casings, said sets of braces being so positioned as to 75 support the sides of said gas bags, and means for filling said gas bags.

JAMES W. DUNDAS.
